UNITED STATES PATENT OFFICE

2,655,707

CONNECTION BETWEEN BAND PARTS AND LOOPS

Irving Rubin, Buffalo, N. Y.

Application February 6, 1951, Serial No. 209,542

1 Claim. (Cl. 24—265)

1

This invention relates to improvements in means for connecting the end of a band of fabric or similar material to a loop of metal or other rigid material.

Connections of this type are commonly used in neckties, garters, or other wearing apparel in which a band is used which may be adjusted to suit the wearer. In connections of this type it is common to provide a loop made of metal or plastic material and which has a slot of sufficient width to permit two bands or two parts of a single band to be passed through the same. Generally one of the parts is adjustable relatively to the loop and the end of the other part is passed through the slot and sewn or otherwise secured to the portion of the other band which has not passed through the slot. This type of connection is objectionable for the reason that when a pull is exerted on the two parts passing through the loop, which is not parallel to the edges of the band, i. e., somewhat diagonally with reference to the length of the band, these parts frequently slide in opposite directions in the slot of the loop to the opposite ends of the slot which produces an unsightly appearance and also changes the adjustment of the band so that the tie, garter or other article will then fit loosely on the wearer.

One of the objects of this invention is to provide a connection between one of the bands or parts and a loop whereby both parts will be maintained in correct relation to the loop so that the slipping of the parts lengthwise of the slot in the loop to the opposite ends thereof and the resulting bunching of the parts at the opposite ends of the slot will be avoided, and which construction at the same time prevents ravelling of the cut end of a band or part.

It is also an object of this invention to employ a loop having a projection extending laterally of the loop and provided with an opening therethrough, and to provide a rigid fastening which extends through such opening for securing the band to the loop.

A further object is to provide an improved method of securing an end of a band part to a loop to form a permanent connection between the band part and the loop and to prevent ravelling of the end of said band part.

Other objects and advantages will be apparent from the following description of one embodiment of the invention and the novel features will be particularly pointed out hereinafter in connection with the appended claims.

In the accompanying drawings:

Fig. 1 is a fragmentary outer face view of a band, such as a neck band of a necktie provided with a connection embodying this invention between an end of the band and a loop.

Fig. 2 is an edge view thereof.

2

Fig. 3 is an inner face view of the part of the band shown in Fig. 1.

Fig. 4 is a longitudinal section thereof taken on line 4—4, Fig. 3.

Figs. 5, 6, 7 and 8 are face views of the end of the band showing the successive folds made therein with relation to the loop before the band is secured to a loop.

Fig. 9 is a face view of an end of the band showing a connection of modified construction between the band and the loop.

Fig. 10 is a longitudinal section thereof, on line 10—10, Fig. 10.

Fig. 11 is a face view of a loop of modified construction.

The usual band for a necktie, garter or the like is made of woven fabric having two band parts 15 and 16, which are connected to each other by means of a loop 17 of any usual or suitable construction. This loop may be made of metal, of a plastic material, or of any other rigid material and has a slot 18 extending lengthwise thereof and crosswise of the band. Both of the band parts are passed through the slot 18 of the loop and the end of the band part 15 after being passed through the loop 17, then extends back on itself to an adjustable buckle 19 to which it is suitably secured. The buckle is adjustable lengthwise of the band part 15 so that the length of the band may be varied by moving the buckle 19 to different portions lengthwise of the band part 15.

In bands of this type as heretofore constructed, the parts of the band passing through the slot in the loop 17, when subjected to a pull in opposite directions against the loop in a diagonal direction, as frequently happens when a person applies the article to himself, had a tendency to move in opposite directions lengthwise of the slot to the opposite ends thereof. This would cause the loop to assume a position at an acute angle to or substantially lengthwise of the band. The two band parts extending through the slot in the loop member 17 would, consequently, be bunched or puckered in the opposite ends of the slot, which would present an unattractive appearance, and furthermore, would increase the length of the band so that the tie, garter or other article would no longer fit properly on the wearer.

In accordance with the present invention, I employ a loop which is provided on a side thereof with a projection 22 which has an opening 24 therein, the sides of which extend transversely of the slot 18 in the loop, and consequently, extend approximately lengthwise of the band. This opening 24 may merge into the slot 18 as shown in Figs. 1 and 3, or may be spaced from the slot, as shown in Fig. 11.

In accordance with my invention, the end of the

3

part 16 of the band is inserted through the slot 18 of the loop and then folded back across the face of the projection 22 of the loop and a suitable fastening is then passed through the two portions of the band part 16 which lie on opposite faces of the projection 22 and through the recess or opening 24 of the projection 22 of the loop 17. This fastening device may be of any usual or suitable type and preferably a small rivet or eyelet 25 is used for this purpose which may be of hollow cylindrical form. One end of the eyelet is flanged over outwardly as shown at 21, and the other end is passed through the fabric and through the opening 24 of the loop, and then turned over as shown at 23 to securely hold the eyelet in the material and the opening in the loop. When this construction is employed, it will be clear that the eyelet or rivet extending through the opening in the projection 22 of the loop will prevent the twisting or turning of the loop relatively to the band part 16. In other words, the eyelet in cooperation with the two layers of the band and the projection of the loop, holds the loop securely in such manner that the slot 18 in the loop will at all times extend substantially perpendicular to the length of the band. This consequently precludes the possibility of the loop assuming an angular position with reference to the length of the band and, therefore, prevents the band parts 15 and 16 from sliding lengthwise of the loop toward the opposite ends of the slot 18 and becoming bunched at such ends. The secure fastening of the band part 16 to the loop 17 by means of the rivet or eyelet, of course, makes it impossible for the part 16 of the band to move lengthwise of the slot 18. Implements for passing an eyelet or other fastening member through fabric and flanging over the leading end thereof are readily available and are, therefore, not herein described.

Preferably the fastening member, such as the rivet or eyelet 25 is also employed to secure a hem or turned over portion of the end of the ribbon part 16 in such a manner as to prevent ravelling of the end of the ribbon. This may be accomplished as shown in Figs. 4 to 8 by first inserting the end portion of the band part 16 through the slot 18 in the loop so that it will lie at one face of the projection 22 of the loops, and then folding the end of the band part 16 about a diagonal line of fold, such for example, as indicated by the broken line 30 in Fig. 5 so that the end of the band then lies across the opposite face of the projection of the loop, as appears in Fig. 6 with a portion 31 of the end of the band folded over diagonally. A further fold of the end of the band part 16 is then made approximately along the broken line 32 so that the end portion 33 of the band part is turned over across the projection 22 of the loop, as shown in Fig. 7. The entire folded end of the band part is then folded over along line 36 in Fig. 8, and with it the loop 17 is also turned through about 180°, thus presenting the appearance shown in Fig. 8. The folded end of the ribbon will, consequently, lie against a portion of the band part which has not been passed through the slot of the loop. By passing a rivet, eyelet or other fastening member through the portions of the band part which overlie the projection of the loop, and through the opening 24 of the loop, a secure fastening such as shown in Fig. 4 is produced.

In place of a hem made of several folds illus-

4

trated in Figs. 5 to 8, it is also possible to prevent ravelling of the end of the band by merely folding the hem or end 40 which has been passed through the slot in the loop backwardly across the end of the projection 22 of the loop to the opposite side of the projection 22, and then passing a rivet or eyelet 25 through the opening 24 and the material at opposite sides thereof as shown in Fig. 10.

In Fig. 11, I have shown a loop 45 of modified construction which may be used in conjunction with my improved connection. This loop has a slot 46 corresponding to the slot 18 shown in Figs. 1 to 10 and an extension 47 at one side of the loop, the extension being provided with a hole or opening 48 which is not connected with or does not merge into the slot 46. It will be obvious that the band part 16 may be connected to this type of loop in the same manner as described in connection with Figs. 1 to 10.

The construction described has the advantage over prior connections between two bands parts or the two ends of a band, that a loop is easily and conveniently held in such relation to one of the band parts so that the loop cannot move to any substantial extent from a position in which the slot therein extends crosswise of the band. The tendency of the two band parts to slide to opposite ends of the slots in the loop is, consequently, eliminated. The construction has the further advantage that it simultaneously hemmed the end of one of the two parts of the band, and furthermore, rivets or eyelets of this type can be very easily passed through parts of the band and through the opening in the projection of the loop.

It will be understood that various changes in the details, materials, and arrangements of parts which have been herein described and illustrated in order to explain the nature of the invention, may be made by those skilled in the art within the principle and scope of the invention, as expressed in the appended claims.

I claim as my invention:

A connection between an end of a fabric band part and a loop of rigid material which has a slot through which said end of the band part is passed, and a projection at a side of said loop intermediate of the ends thereof and having an opening through said projection, said band part having an end portion thereof lying at one face of said projection and passed through said slot and folded back across the other face of said projection, a hem in the end of said band formed by a pair of successive diagonal folds in the end of said band part, said hem lying across said projection and said opening therein, and a metal fastening member which extends through said portions of said band part which lie at opposite faces of said projection, said hem and said opening in said projection holding said loop in substantially fixed relation to said band part.
